UNITED STATES PATENT OFFICE.

LOUIS VERGNAUD, OF PARIS, FRANCE, ASSIGNOR TO ETABLISSEMENTS JACOB HOLTZER, OF PARIS, FRANCE, A CORPORATION.

PROCESS AND APPARATUS FOR THE MANUFACTURE OF CRUCIBLES.

1,392,541.

Specification of Letters Patent.

Patented Oct. 4, 1921.

Application filed July 9, 1919. Serial No. 309,594.

To all whom it may concern:

Be it known that I, LOUIS VERGNAUD, a citizen of the French Republic, residing at 43 Rue des Marais, Paris, France, have invented certain new and useful Improvements in Processes and Apparatus for the Manufacture of Crucibles, of which the following is a specification.

In the methods employed hitherto for the manufacture of crucibles by pressing a paste of clay or other substance, the said paste is placed in a metal mold having the shape of the desired crucible, and it is pressed by one or more mandrels which are arranged concentrically in relation to the mold and are forced successively into the paste. The pressing is effected by means of a power press or by hand.

In pressing by means of a power press the mandrel is forced gradually into the paste by moving either the mandrel or the mold by means of a screw or a hydraulic ram, but that method has the drawback that if the paste is comparatively stiff, the shaping of the paste does not take place uniformly and the paste is liable to crack, while if the paste is very soft it is not compressed sufficiently to acquire the compactness that is requisite in order to assure that it shall have a long "life" when subjected to fire heat, and this drawback is particularly appreciable in the case of crucibles intended for use in melting steel or metal alloys of high melting points.

In manufacturing by hand, the mandrel is forced into the paste in a discontinuous manner, that is to say, by successive impacts, and generally a plurality of mandrels of different and gradually increasing sections are employed in order that the successive shaping operations that are necessary to convert the solid clay block into the finished crucible shall be performed as regularly as possible; but since this work is done by hand the output is of course very low. Moreover as the centering of the mandrel depends on the skill of the workman, it is faulty and has the result that the walls of the crucible are not uniform in thickness and the crucible develops weaknesses. It has been proposed for the purpose of guiding the mandrel which is struck by the workman, to provide the lower end of the mandrel with a stem that passes through the crucible. This arrangement however necessitates the formation of a hole in the bottom of the crucible

which has to be stopped with a plug of clay after the crucible is formed; but this plugging is difficult and requires skill, and there is a difficulty in insuring a perfectly homogeneous and absolutely intimate incorporation of the bottom plug with the mass of the crucible.

The present invention has for its object to provide an improved process which will avoid those drawbacks in the mechanical manufacture of crucibles, and more particularly of crucibles for melting steel, and also an improved apparatus for carrying this improved process into effect by means of which the centering will be absolutely uniform and regular and the operation continuous.

The improved process consists in using, for pressing the paste inside the mold, a plurality of mandrels having the same or gradually different sections, provided with perfectly centered and guided stems, upon which blows are delivered successively by hammers of different lengths to which a regular alternating motion is imparted by mechanical means; the total length of each stem and its mandrel increasing gradually as the crucible passes under each mandrel.

In the accompanying drawings which illustrate by way of example a practical construction of the improved apparatus:

Figure 1 is an end elevation of a portion of the apparatus.

Fig. 2 is an elevation showing the mandrels and the means for guiding same; and

Fig. 3 is a plan of the apparatus.

In the illustrated example, the apparatus comprises three mandrels *a*, *b*, *c* of different and gradually increasing sections. The mandrels may however be in any desired number and of equal sections without departing from the nature of the invention.

The crucible molds for the set of the three mandrels shown, are five in number, and are mounted on a round plate *d* which is arranged to be rotated around a vertical axle *e*. The clay paste is placed in each mold as it passes the point 1, and the charged mold is carried in succession under the mandrels at 2, 3, 4, during which travel each of the mandrels *a*, *b*, *c* is forced into the paste in a gradually increasing degree until the forcing in of the mandrel *c* situated at 4 has completed the finished internal shape of the crucible. When the crucible arrives at 5 it is removed and taken to the drying place.

Each mandrel has a stem *f* whose head

g is struck repeated blows by a hammer *h*. The total lengths of each of the mandrels *a*, *b*, *c* and its respective stem *f* are different and increase gradually from 2 to 4 in such 5 a way that the same driving of each of the stems of the mandrels by blows of the successive hammers will force each mandrel in by an extent that increases along the points 2 to 4.

10 The hammers *h* are mounted at the ends of the long arms of levers *l* that are lifted automatically after each blow by the cams *m* of a wheel *n* rotating on a horizontal axis.

15 For the purpose of guiding the stems of the mandrels and centering the latter accurately in the crucibles, one or more guide plates *i* are mounted slidably on the vertical axle *e* of the frame of the apparatus.

20 The stems work with slight friction in these guide plates whereby they are guided and centered with absolute accuracy.

The improved apparatus allows of:—

First, working with a comparatively stiff 25 paste;

Second, reproducing in an absolutely regular and adjustable manner at will the effects of the repeated blows of a crucible maker working by hand with a mallet;

30 Third, effecting an absolutely regular centering of the mandrel, while dispensing with the hole in the bottom of the crucible for the passage of a guiding stem;

Fourth, employing any desired number 35 of mandrels so that the final shape of the crucible may be produced as gradually as may be desired, so that each portion of the wall of the crucible may be subjected to a uniform pressure;

40 Fifth, effecting the manufacture of the crucible in a continuous manner.

Having now particularly described and set forth the nature of my said invention and in what manner the same is to be performed I declare that what I claim is:—

1. A process for forming crucibles consisting in placing the material, from which the crucible is to be formed, in a mold member and successively introducing mandrel

members of successively increasing sizes 50 into the material in the mold, and moving one of said members relatively to the other member while a mandrel is in engagement with said material for causing said material to be compressed.

2. An apparatus for the manufacture of crucibles of clay paste, comprising on a fixed frame, guides wherein the stems of a series of mandrels of different lengths can slide, and are subjected to the repeated 60 blows of hammers delivered at adjustable regular intervals, whereby a gradual compression is exerted upon the paste constituting the crucibles arranged on a moving plate that brings each crucible under each 65 mandrel in turn.

3. A process for forming crucibles consisting in placing the material, from which the crucibles are formed, into molds, bringing said molds into alinement successively 70 with mandrels of successively increasing sizes, and depressing said mandrels while they are in engagement with the material in the molds for causing the material to be compressed and shaped.

4. A process for forming crucibles consisting in placing the material from which the crucibles are formed into a plurality of molds, simultaneously introducing mandrels of successively increasing sizes into said 80 molds or into the material contained in the molds and bringing the material in each mold successively into engagement with the mandrels of successively increasing sizes.

5. An apparatus for producing crucibles 85 including a turn-table adapted to support a series of molds arranged in circular formation, a series of vertical guides arranged above said molds, vertically reciprocating shafts slidably mounted in said guides, 90 mandrels of successively increasing sizes carried by said shafts and designed to enter said molds for compressing plastic material carried thereby, and hammers engageable with the heads of said shafts for forcing the 95 mandrels downwardly into the material contained within the molds.

LOUIS VERGNIAUD.
